United States Patent Office

Des. 185,598
Patented June 30, 1959

185,598

CONTROL INSTRUMENT

Henry Dreyfuss, South Pasadena, Calif., assignor to Minneapolis-Honeywell Regulator Company, Minneapolis, Minn., a corporation of Delaware

Application November 5, 1956, Serial No. 43,664

Term of patent 14 years

(Cl. D52—7)

FIG. 1

FIG. 2

Figure 1 is a perspective view of a control instrument embodying my new design looking from the upper right; and

Figure 2 is a perspective view of my design looking from the lower left.

The characteristic features of the design for the control instrument disclosed reside in the transparent face panel and the front panel disposed thereunder having the configurations and arrangements shown.

I claim:

The ornamental design for a control instrument, substantially as shown and described.
